LIGHTING FIXTURE CONTROLLER FOR CONTROLLING COLOR TEMPERATURE AND INTENSITY

CROSS REFERENCE TO RELATED APPLICATIONS

This application is a continuation of U.S. application Ser. No. 16/811,076, title, Lighting Fixture Controller for Controlling Color Temperature and Intensity, filed Mar. 6, 2020, which claims priority to U.S. Provisional App. No. 62/815,783, titled “Lighting Fixture Controller for Controlling Color Temperature and Intensity” and filed on Mar. 8, 2019, which are incorporated herein in their entirety.

TECHNICAL FIELD

This disclosure relates generally to the field of lighting fixtures. More specifically, this disclosure relates to controlling multiple groups of LEDs to produce different color temperatures and intensities using a single lighting fixture.

BACKGROUND

Lighting fixtures can produce different color temperatures of white light and different intensities to suit the preferences of different consumers or activities. For example, a cool white light may be preferred by some consumers or appropriate for some activities, whereas a warm white light may be preferred by other consumers or appropriate for other activities. Similarly, a consumer might want to reduce the intensity of a lighting fixture in certain circumstances or to increase the intensity of the lighting fixture in other circumstances. In some instances, different lighting fixtures are required to provide light with different color temperatures and intensities.

SUMMARY

Certain embodiments involve a light fixture controller configured for controlling the color temperature and the intensity of a light fixture. The light fixture includes a first LED group, a second LED group, and a driver for powering the first LED group and the second LED group. The first LED group includes a first set of LEDs and configured to produce light at a first color temperature. The second LED group includes a second set of LEDs and is configured to produce light at a second color temperature. The light fixture controller includes one or more interfaces configured for receiving a color temperature setting and an intensity setting for the light fixture. The light fixture controller further includes a microcontroller configured for generating control signals based on the color temperature setting and the intensity setting for the light fixture. The control signals include a first control signal and a second control signal. The first control signal is configured for controlling an on/off state of the first LED group by controlling an open/closed state of a first switch connected to the first LED group. The second control signal is configured for controlling an on/off state of the second LED group by controlling an open/closed state of a second switch connected to the second LED group. The first control signal only turns on the first LED group for a first duration of an ON/OFF cycle and the second control signal only turns on the second LED group for a second duration of the ON/OFF cycle. The ratio between the first duration and the second duration is determined based on the color temperature setting for the light fixture. The ON/OFF

2

cycle includes multiple time periods, and during each of the multiple time periods, at least one LED group of the light fixture is set to be on and at least one another LED group of the light fixture is set to be off. The control signals further include a dimming control signal configured for controlling the driver of the light fixture to adjust the current flowing through the first LED group and the second LED group based on the intensity setting for the light fixture.

These illustrative embodiments are mentioned not to limit or define the disclosure, but to provide examples to aid understanding thereof. Additional embodiments are discussed in the Detailed Description, and further description is provided there.

15 BRIEF DESCRIPTION OF THE DRAWINGS

Features, embodiments, and advantages of the present disclosure are better understood when the following Detailed Description is read with reference to the accompanying drawings, where:

FIG. 1 depicts an example of a circuit that uses a controller presented herein to control the color temperature and intensity of a light fixture, according to the present disclosure.

FIG. 2A depicts an example of controlling the color temperature of a light fixture by a controller via pulse width modulation signals, according to the present disclosure.

FIG. 2B depicts another example of controlling the color temperature of a light fixture by a controller via pulse width modulation signals, according to the present disclosure. FIGS. 2A and 2B are collectively referred to herein as FIG. 2.

FIG. 3 depicts another example of a circuit that uses a controller presented herein to control the color temperature and intensity of a light fixture, according to the present disclosure.

FIG. 4A depicts an example of shifting or correcting the light pattern of a light fixture using a controller presented herein.

FIG. 4B depicts an example of changing the light concentration of a light fixture using the controller presented herein.

FIG. 4C depicts an example of changing the light direction of a light fixture using the controller presented herein.

FIG. 5 depicts an example of a “Push-N-Program” interface device that can be connected to and program a controller to specify various settings for the light fixture, according to the present disclosure.

FIG. 6 depicts another example of an interface device that can be connected to and program the controller to specify various settings for the light fixture, according to the present disclosure.

55 DETAILED DESCRIPTION

Briefly described, the present disclosure generally relates to a controller that is configured for controlling multiple light-emitting diode (LED) groups of a light fixture with a single-channel driver to produce different color temperatures and intensities. Based on a color temperature setting, the controller can control the flow of the output current of the driver through each of the LED groups so that the light fixture produces light with a color temperature that matches the color temperature setting of the controller. In addition, the controller further controls the current flowing through the groups of LEDs to control the intensity of the light fixture based on an intensity setting at the controller.

In some configurations, a controller is configured to control multiple color temperature switches in order to control the color temperature of the light fixture. Each color temperature switch is configured to control the current flow of the corresponding LED group. For example, the controller can control the color temperature switches so that at a given time, only a first LED group is ON while the remaining LED groups are OFF and, at another time, only a second LED group is ON while the remaining LED groups are OFF. The time duration when the first LED group is ON and the time duration when the second LED group is ON determine the resulting color temperature of the light fixture. As such, by controlling the current flow through each of the LED groups, the controller can control the color temperature of the light fixture to match the color temperature setting of the controller.

To control the intensity of the light fixture, in one configuration, the controller provides a dimming control input to the driver of the light fixture, such as a 0-10V dimming control input. The dimming control input can cause the driver to adjust the current output by the driver and flowing through the LED groups thereby adjusting the intensity of the light fixture. In another configuration, the LED groups of the light fixture can each be connected to one or more intensity switches that control the ON/OFF state of a portion of LEDs in each LED group. The controller can thus control the intensity of the light fixture by controlling the number of LEDs in an LED group that are ON via the intensity switches. Similarly, the controller can also control other aspects of the light fixture, such as the light pattern, light distribution or light direction by controlling these intensity switches.

The controller can be pre-set or programmed through various interfaces such as switches, tactile buttons, break-away PCB tabs or traces. The controller can also be controlled by advanced features such as digital wired network communication interfaces, wireless communication interfaces, optical communication interfaces, an OEM “push-on-programmer” or a wireless NFC-TAG interface. External control or programming interface devices could be made through cell phones, computer or lighting controller interfaces, or other OEM designed devices.

By using the controller presented herein, different outputs that are traditionally provided by different light fixtures, such as different color temperatures, intensities, light patterns, concentrations, and so on, can be provided by a single light fixture. Further, the controller presented herein does not require a special driver to achieve these multiple outputs of the light fixture. Rather, a single-channel off-the-shelf driver can be used in the light fixture and controlled by the controller.

Referring now to the figures, FIG. 1 depicts an example of a circuit that uses a controller presented herein to control the color temperature and intensity of a light fixture 100. The light fixture 100 includes a single channel LED driver 102 that provides a current to multiple LED groups 104A-104C, which may be referred to herein individually as an LED group 104 or collectively as the LED groups 104. An LED group 104 may include multiple LEDs. The LEDs in an LED group 104 may be connected in series, in parallel, or in any combination thereof. Individual LEDs in an LED group 104 may have the same color temperature or may have different color temperatures. The number of LEDs in an LED group may be the same or differ between LED groups within the same light fixture so long as the LED groups appear balanced to the driver. When the LED group 104 is powered, the LEDs of the group collectively provide light at a color

temperature. The disclosure is also applicable to light fixtures that use other types of lighting elements including, but not limited to, organic light-emitting diodes (OLEDs).

In some configurations, different LED groups 104 have different color temperatures. In an example where the LED groups 104 have two LED groups such as LED group 104A and LED group 104B, LED group 104A can be configured to produce light with a color temperature of 5000K and LED group 104B can be configured to produce light with a color temperature of 2700K. Color temperatures of 5000K and above are generally considered “cool white”, and color temperatures between 2000K-3000K are generally considered “warm white.” By controlling the ON/OFF cycles of LED group 104A and LED group 104B, different color temperatures of the light fixture 100 can be achieved.

To control the ON/OFF state of the LED groups 104, the light fixture 100 shown in FIG. 1 further includes multiple switches 106A-106C, which may be referred to herein individually as a switch 106 or collectively as the switches 106. Each of the switches 106 is connected in series with the LEDs in the corresponding LED group and provides a switchable path between the output of the driver 102 and the corresponding LED group 104 thereby controlling the ON/OFF state of the corresponding LED group 104. In the example shown in FIG. 1, switch 106A controls the ON/OFF state of LED group 104A, switch 106B controls the ON/OFF state of the LED group 104B, and switch 106C controls the ON/OFF state of the LED group 104C.

The light fixture 100 can further include a controller 108 for controlling various aspects of the light fixture 100, such as the color temperature, the intensity, light pattern, light distribution, light direction and so on. In one configuration, the controller 108 is a microcontroller-based device that is compatible with off-the-shelf LED drivers to add various functionalities to the light fixture 100. The controller circuitry can be integrated on an LED light engine board or on a stand-alone printed circuit board (PCB) (not shown in FIG. 1). The controller 108 can be self-powered or can use power from the LED driver 102. In the example shown in FIG. 1, a power supply component 110 is added to the light fixture 100 to convert the output of the LED driver 102 to a power supply that can be used to power the controller 108. In other examples, the controller 108 can be powered by an external power source, such as an external battery.

The controller 108 can be configured to accept various control inputs, such as a color temperature control 112 and an intensity control 114. The color temperature control 112 can specify a color temperature setting so that the controller 108 can control the light fixture 100 to produce light with a color temperature that matches the color temperature setting. Similarly, the intensity control 114 can specify an intensity setting so that the controller 108 can control the light fixture 100 to produce light with an intensity that matches the intensity setting. In one example, the controller 108 can be pre-set or programmed with the intensity and color temperature settings or other settings through various interfaces, such as slide switches or PCB jumpers. Detailed examples of the interfaces that can be utilized to set or program the settings of the controller 108 are provided below with regard to FIGS. 5 and 6.

In the example shown in FIG. 1, the controller 108 controls the intensity of the light fixture 100 based on the intensity setting of the controller 108 through a dimming control signal 116 sent to the LED driver 102. The dimming control signal 116 can be, for example, a 0-10V control signal that varies between 0 to 10V. Based on the dimming control signal 116, the LED driver 102 controls the amount

of current provided to the LED groups, for example, in proportion to the voltage value of the dimming control signal 116. As such, a dimming control signal 116 having a 10V can lead to a full intensity of the light fixture 100, whereas a 5V dimming control signal 116 results in a 50% intensity of the light fixture 100. Other types of dimming inputs are also possible.

FIG. 1 further illustrates that the controller 108 controls the color temperature of the light fixture 100 through outputting control signals to control the switches 106 of the LED groups 104. As shown in FIG. 1, the controller 108 can output multiple control signals each of which is configured to control one of the switches 106. A control signal of the controller 108 can control the open/closed state of the corresponding switch 106 thereby controlling the on/off state of the corresponding LED groups. When a switch 106 is closed, the current provided by the LED driver 102 can flow through the corresponding LED group to drive the LED group in the ON state to emit light. When the switch 106 is open, the current provided by the LED driver 102 does not flow through the corresponding LED group and thus the LED group stays in the OFF state without emitting light.

To achieve the color temperature specified in the color temperature setting, the controller 108 determines an ON/OFF cycle. At a given duration of the cycle, the controller 108 can control one of the LED groups 104 to be ON while the remaining LED groups 104 are kept OFF. At another duration of the cycle, another LED group can be set ON while the remaining LED groups are kept OFF. By controlling the ON/OFF cycle of the LED groups, the controller 108 can control the light fixture 100 to produce light at a certain color temperature. To change the color temperature of the light fixture 100, the controller 108 can adjust the ON/OFF cycle to change the time duration for the individual LED group to be in an ON state. Because the switches 106 are utilized here to control the color temperature of the light fixture 100, these switches are also referred to herein as “color temperature switches 106.” Additional details regarding the operations of the light fixture 100 are provided below with regard to FIGS. 2-6.

FIG. 2A illustrates an example of controlling the color temperature of a light fixture 100 by controlling the open/closed state of the color temperature switches 106 connected to the LED groups of the light fixture using pulse width modulation (PWM) signals. In this example, the light fixture 100 has two LED groups, referred to herein as channel A LED group and channel B LED group. Each of the two LED groups has a color temperature switch connected in series with the LEDs in the corresponding LED group. The controller 108 controls the two color temperature switches using a PWM signal with a frequency f , such as 400 Hz, and an ON/OFF cycle $T=1/f$. In the example shown in FIG. 2A, within one ON/OFF cycle, one of the LED groups is ON and the other is OFF. In particular, channel A LED group is in the ON state for the first 70% of the cycle time and channel B LED group is in the ON state for the remaining 30% of the cycle time. If the color temperature of channel A LED group is 2700K and the color temperature of channel B LED group is 6500K, the light fixture 100 can produce light with a color temperature of 2700K for 70% of the cycle and a color temperature of 6500K for 30% of the cycle. The combined color temperature may become, for example, 3400K. It should be noted that the combined color temperature value is also determined by the respective flux of the LED groups. As such, the open/close cycle of the switches 106 connected to the LED groups can be determined based on the target combined color temperatures of the light fixture as well as

the flux of the LED groups. Due to the high frequency of the PWM signal which is typically on the scale of several hundreds of Hz, the changes between the two color temperatures within a cycle are unnoticeable to human eyes and only the combined color temperature is perceivable by a user.

FIG. 2B illustrates another example of controlling the color temperature of the light fixture 100 by controlling the open/closed state of the switches 106 using pulse width modulation (PWM) signal. In this example, the light fixture 100 has N LED groups, denoted as channel A, channel B, ..., channel N in FIG. 2B. The cycle of the PWM signal is divided into N time durations and within each time duration, one of the N LED groups is ON whereas others are OFF. The total ON time of the N LED groups equals to the time of an ON/OFF cycle. The color temperature of the light fixture 100 can thus be determined based on the ON time of the N LED groups, their respective color temperatures, and their respective flux.

It should be understood that while the examples in FIGS. 2A and 2B show one LED group is ON at a given time duration of the ON/OFF cycle, multiple LED groups can be turned on and the output color temperature of the light fixture 100 can be determined in a similar way as described above, i.e. by determining the color temperature for each time duration of the cycle and calculating the combined color temperature based on the percentage of each time duration in the entire cycle. Likewise, for a given color temperature, the controller can calculate the duration for each LED group to be ON within a cycle based on the color temperature and flux of individual LED groups, thereby generating the control signals to control the open/closed state of the switches 106.

FIG. 3 depicts another example of a circuit that uses a controller presented herein to control the color temperature and intensity of a light fixture 300. In this example, the light fixture 300 has two LED groups 104D and 104E. Each of the two LED groups includes multiple LEDs that are similar to the LEDs described above with regard to FIG. 1. Other components of the light fixture 300, such as the LED driver 302 and the power supply 330 are also similar to the corresponding components of the light fixture 100 shown in FIG. 1.

Different from the light fixture 100 shown in FIG. 1, each LED group of the light fixture 300 includes multiple switches 310A-310F that are connected in series to a portion of the LEDs in an LED group and in parallel to other portions of the LEDs in the group. For example, the switch 310A is connected in series with the top 60% LEDs of the LED group 104D and in parallel to the remaining 40% LEDs in the group. As a result, when the switch 310A is closed (and other switches in LED group 104D are open), the current from the driver 302 will flow through the top 60% LEDs but not the remaining 40% LEDs. When the switches 310A and 310C are open and switch 310E is closed, the current from the driver 302 will flow through all the LEDs in the LED group 104D. In this way, the switches 310 can be utilized to control the number of LEDs that are on thereby controlling the intensity of the light fixture 300. Because the switches 310 can be utilized to control the intensity of the light fixture 300, they are also referred to herein as “intensity switches 310.”

The controller 308 of the light fixture 300 is also similar to the controller 108 of the light fixture 100 shown in FIG. 1 except that the controller 308 is further configured to control the intensity switches 310. As shown in the example of FIG. 3, the controller 308 generates output signals 320A-

320F for controlling the intensity switches 310A-310F, respectively. If the intensity setting of the controller 308 is set to be 60% intensity, the controller 308 can control the intensity switches 310A and 310B to be closed and other switches are open so that only the top 60% LEDs of each LED group are on thereby generating light with 60% intensity. In one configuration, the open/closed states of the intensity switches 310A and 310B are synchronized so that they are closed and opened at the same time. Similarly, the open/closed states of the intensity switches 310C and 310D are synchronized and the open/closed states of the intensity switches 310E and 310F are also synchronized. This can ensure that the voltages on the different LED groups are balanced to avoid disturbance to the LED driver 302.

Because the intensity of the light fixture 300 can be controlled using the intensity switches, the dimming control signal provided by the controller to the LED driver can be eliminated as shown in FIG. 3. In other configurations, the dimming control signal can also be provided to the LED driver as an additional mechanism to control the intensity of the light fixture 300.

It should be understood that while FIG. 3 only shows two LED groups, the light fixture 300 can include more than two LED groups and controlling the multiple LED groups can be performed similarly. For example, the light fixture 300 can include a third LED group with a similar configuration as the LED groups 104D and 104E, i.e. containing three intensity switches placed at 60%, 80% and 100% intensity positions as the intensity switches of the LED groups 104D and 104E. To control this third LED group, the controller 308 can include three additional outputs to control the three intensity switches, respectively. More LED groups can be added similarly.

It should be further understood that while the above examples use three intensity switches to control the intensity of the light fixture 300 at 60%, 80%, and 100% intensities, more or fewer than three intensity switches can be added to each LED group at other locations to control the intensity of the light fixture 300 to be at any intensity values, such as 10%, 20%, 50%, and so on.

To control the color temperature of the light fixture 300 shown in FIG. 3, the controller 308 can control the intensity switches that are closed in the same way as the controller 108 controls the color temperature switches 106 as described above with regard to FIGS. 1, 2A and 2B. In other words, the controller 308 can control the intensity switches that should be closed by following the ON/OFF cycle described with regard to FIG. 2A. For example, if the light fixture 300 is set at 60% intensity, the controller 308 controls the switches 310A-310B to be closed and keeps the switches 310C-310F open. The controller further controls the switches 310A and 310B to follow an open/close cycle, such as the cycle shown in FIG. 2A, so that only one LED group has 60% of LEDs on at a given time point. The time duration that one group is on and the other is off is determined by the color temperature settings. In this configuration, the intensity switches 310 are also used to control the color temperature of the light fixture.

In another configuration, a separate color temperature switch (not shown in FIG. 3) can be connected to each LED group, for example, between point 318 and the first LED in each group. In this way, the controller 308 only needs to control these separate color temperature switches as described with regard to FIG. 2 and controls the intensity switches to remain on or off based on the intensity setting of the light fixture.

In the example shown in FIG. 3, the intensity of the light fixture 300 is essentially controlled by turning on some of the LEDs while turning off other LEDs. In some fixture configurations, this can cause pixelation artifacts where some portions of the light fixture 300 are bright whereas other portions of the light fixture 300 are dark. This problem can be addressed by adding a mixing chamber (not shown in FIG. 3) to the light fixture 300 to diffuse the light emitted by the LED groups so that the location of the light source, i.e. the LEDs, cannot be discerned from outside the light fixture 300.

In addition to controlling the intensity of the light fixture 300, the intensity switches shown in FIG. 3 can also be utilized to control other aspects of the light fixture 300. For example, the controller can be utilized to perform dynamic optical element control of the light fixture to control the light distribution such as the light pattern, light concentration, light direction, etc. FIGS. 4A-4C illustrate examples of controlling the light distribution of a light fixture that is configured similarly to the light fixture 300. That is, the light fixture has multiple LED groups, each LED group having one or more intensity switches that can be controlled by the controller to turn on or off portions of the LEDs in each LED group and the different portions of the LEDs located at different locations.

FIG. 4A depicts an example of shifting or correcting the light pattern of a light fixture 400A using a controller presented herein. In this example, the light fixture 400A can include multiple LED groups whose LEDs are distributed along the peripheral area of the light fixture 400A. Depending on the patterns to be adjusted, the LEDs of the LED groups can be connected in parallel or in series with multiple intensity switches. Each of the intensity switches can be configured to control the ON/OFF state of a section of the LEDs. The controller can be programmed to control the light fixture 400A to produce a light pattern shown on the left side of FIG. 4A, i.e. section A is dark whereas sections B and C are bright. Under this setting, the controller can control the intensity switches so that the LEDs in section A are off and the LEDs in sections B and C are on. If the controller is further programmed to change the light pattern to the one shown on the right side of FIG. 4A, the controller can control the intensity switches so that the LEDs in section IV are off and the LEDs in sections I, II and III are on. Other light patterns can be created and controlled in a similar way.

FIG. 4B depicts an example of changing the light concentration of a light fixture 400B using the controller presented herein. In this example, the light fixture 400B can include multiple LED groups whose LEDs are distributed across the entire LED board of the light fixture. These LEDs can be connected in parallel or in series with multiple intensity switches. For example, a portion of an LED group can be installed in the center area of the light fixture pointing to a center point of the light fixture. Another portion of the LED group can be scattered in the peripheral area of the light fixture pointing away from the center point. When only the center LEDs are on, concentrated light is produced from the light fixture, and when only the peripheral LEDs are on, dispersed light is produced from the light fixture. Intensity switches can be connected to each LED group so that the controller can change the concentration of the light fixture (i.e. concentrated lights or dispersed lights) by changing the open/closed state of the intensity switches. With such a configuration, the controller can thus be programmed to control the concentration of the light fixture by controlling the intensity switches of the LED groups.

FIG. 4C depicts an example of changing the light direction of a light fixture 400C using the controller presented herein. In this example, the light fixture can include multiple LED groups whose LEDs are distributed across the surface of the light fixture. A first portion of the LEDs in an LED group are installed pointing downward whereas the second portion of the LEDs are installed pointing upward. As a result, when only the first portion of the LEDs are on, the light fixture can produce downwardly directed light. When only the second portion of the LEDs are on, the light fixture can produce upwardly directed light. To switch the light fixture between the different light directions, intensity switches can be connected to each LED group so that the controller can change the light direction of the light fixture by changing the open/closed state of the intensity switches to have one portion of the LEDs on with the other portion off. With such a configuration, the controller can thus be programmed to control the light direction of the light fixture by controlling the intensity switches of the LED groups.

As discussed above, in order for the controller to control the color temperature, intensity and other properties of the light fixture, the controller can be programmed with settings for these varies properties of the light fixture through various interfaces. FIG. 5 illustrates a “Push-N-Program” interface device 502 that can be connected to a controller 504 and program the controller 504 to specify various settings for the light fixture, such as the color temperature and the intensity. The controller 504 can be a controller described above with regard to FIGS. 1-4C, or any combination thereof.

The middle figure of FIG. 5 shows a top view of the interface device 502 which includes multiple buttons for controlling the controller 504. For example, the PWR button can be configured to control the ON/OFF state of the interface device 502, the SW A button and the SW B button can each be set to an “ON” or “OFF” state, resulting in four combinations of the outputs of the interface device 502 (i.e. SW A ON and SW B ON, SW A ON and SW B OFF, SW A OFF and SW B ON, SW A OFF and SW B OFF). These four combinations can be used to program the controller 504 to up to four preset functions. For example, these four combinations can program the controller 504 to have four different color temperature and intensity settings. A specific state of the SW A button and the SW B button can thus set the controller to one of the four settings to control the light fixture accordingly.

The left figure of FIG. 5 illustrates a cross sectional view of the interface device 502 which shows that the interface device 502 is powered by a battery in this example. The battery can any type of battery, such as a 9V battery, a 12V battery and so on. The interface device 502 can also be powered by other forms of external power supplies. Since the interface device 502 is powered by an external power source, it can be configured to provide power to the controller 504 so that the controller 504 does not need to obtain power from the light fixture during programming. As shown in FIG. 5, the interface device 502 can be pushed into the PCB of the controller 504. In one example, an LED 506 on the PCB can be configured to change the blink pattern to indicate the successful programming of controller 504 using the interface device 502.

FIG. 6 illustrates another example of an interface device that can be connected to and program the controller 610 to specify various settings for the light fixture. In the example shown in FIG. 6, a near field communication (NFC)-TAG interface 602 is utilized to program the controller 610. In order to enable the NFC, an NFC-TAG antenna 604 can be installed inside the light fixture or mounted on the outside of

the light fixture. A mobile device 606 such as a smartphone can communicate with the controller through the NFC-TAG to program the controller. A PCB QR sticker 608 can be affixed to the printed circuit board (PCB) of the controller 610 so that the mobile device 606 can scan it to obtain information about the specific capabilities of the controller 610 and the light fixture, such as the supported color temperature and intensity settings or other parameters. Other components can be added to the PCB of the controller 610 to facilitate the programming of the controller.

In one example, the controller can be programmed with the proper firmware and the NFC programmed settings can be set to a default value, such as 50% of intensity. When installing the light fixture, an installer can scan the QR code to obtain the information about the light fixture and the controller. The installer can further use a phone app to program the NFC TAG to set the light fixture at a specific color temperature or intensity level. By implementing the interface device in this way, no special tools are required to program the controller. Further, the information needed for configuring the controller is readily available by scanning the QR code. As a result, a single light fixture can be utilized to provide multiple light outputs which are traditionally provided by multiple light fixtures.

It should be understood that the example interfaces shown in FIGS. 5 and 6 are for illustration purposes and should not be construed as limiting. Various other types of interfaces can also be utilized to pre-set or program the controller. The 30 interfaces that can be utilized include, but are not limited to, slide switches, PCB Jumpers, tactile push-button programming, potentiometer, break away PCB tabs, strip-away PCB traces, changeable daughter-card PCB, IR-communication, NFC-Tag programming, capacitive touch pad on PCB, push-on programmer, Bluetooth wireless, wired network, digital addressable lighting interface (DALI), etc. In addition to standalone interfaces, control systems can also be utilized. For example, the circuit of the light fixture or the controller can be changed to allow DALI inputs to program the 40 controller.

It should be further understood that the controller presented herein can be adapted with additional functionality such as wireless controls, expanded light engine configurations, communications interfaces, integrated sensors, alternate means of interfacing with the controller (human interface devices), etc.

GENERAL CONSIDERATIONS

50 The color temperatures, intensities, number of LED groups, number and arrangements of LEDs in an LED group, and currents used in the above examples are exemplary. Other implementations may use different values, numbers, or arrangements and may use other types of 55 lighting elements. The fixture may be any type of a fixture, including a linear fixture, a downlight, or a flush mount fixture. The LEDs of the different LED groups may be arranged so that the LEDs from different groups are spatially interspersed in the fixture or may be arranged so that LEDs 60 from different groups are separated in the fixture. Other light characteristics other than color temperature and intensity may also be changed or controlled.

A switch may use any type of component or combination of components to provide the described states or switching functions. A switch may include any type of mechanical, electrical, or software switch and a switch may be controlled or set directly or indirectly. A switch may be controlled by

11

a user or by another component that is either part of the fixture or remote from the fixture.

Although the foregoing describes exemplary implementations, other implementations are possible. It will be appreciated that those skilled in the art, upon attaining an understanding of the foregoing, may readily produce alterations to, variations of, and equivalents to the described aspects. Accordingly, it should be understood that the present disclosure has been presented for purposes of example rather than limitation and does not preclude inclusion of such 10 modifications, variations, and/or additions to the present subject matter as would be readily apparent to one of ordinary skill in the art.

Unless specifically stated otherwise, it is appreciated that throughout this specification discussions utilizing terms such as "processing," "computing," "calculating," "determining," and "identifying" or the like refer to actions or processes of a computing device, such as one or more computers or a similar electronic computing device or devices, that manipulate or transform data represented as 15 physical electronic or magnetic quantities within memories, registers, or other information storage devices, transmission devices, or display devices of the computing platform.

The use of "adapted to" or "configured to" herein is meant as an open and inclusive language that does not foreclose devices adapted to or configured to perform additional tasks or steps. Additionally, the use of "based on" is meant to be open and inclusive, in that a process, step, calculation, or other action "based on" one or more recited conditions or values may, in practice, be based on additional conditions or values beyond those recited. Headings, lists, and numbering included herein are for ease of explanation only and are not meant to be limiting.

What is claimed is:

1. A light fixture controller configured for controlling color temperature, intensity, and light distribution of a light fixture, the light fixture controller comprising:

one or more interfaces configured for receiving a color temperature setting, an intensity setting, and a light distribution setting for the light fixture, wherein the light fixture comprises a first light-emitting diode (LED) group, a second LED group, a driver for powering the first LED group and the second LED group, the first LED group comprising at least two portions of a plurality of LEDs configured to produce light at a first color temperature wherein a first portion of the first LED group is located at a first area of the light fixture and a second portion of the first LED group is located at a second area of the light fixture, the second LED group comprising at least two portions of a plurality of LEDs configured to produce light at a second color temperature wherein a first portion of the second LED group is located at the first area of the light fixture and a second portion of the second LED group is located at the second area of the light fixture, and one or more switches located within the light fixture operably connected to the portions of the plurality of LEDs comprising the LED groups; and

a microcontroller configured for generating control signals based on the light distribution setting, the color temperature setting, and the intensity setting for the light fixture, wherein the control signals comprise: a first light distribution control signal for controlling an open/closed state of a first switch operably connected to the first portion of the first LED group and a second light distribution control signal for controlling an open/

12

closed state of a second switch operably connected to the first portion of the second LED group, wherein the first light distribution control signal enables the first portion of the first LED groups to receive power from the driver; and

the second light distribution control signal enables the second subset portion of the second LED group to receive power from the driver;

a first control signal for controlling a first color temperature switch connected in series with the first LED group and a second control signal for controlling a second color temperature switch connected in series with the second LED group, wherein

the first control signal turns on the first color temperature switch only for a first duration of an ON/OFF cycle and the second control signal turns on the second color temperature switch only for a second duration of the ON/OFF cycle, wherein the ON/OFF cycle comprises multiple time periods, and during each of the multiple time periods, at least one LED group of the light fixture is set to be on and at least one another LED group of the light fixture is set to be off, and

a ratio between the first duration and the second duration is determined based, at least in part, upon the color temperature setting for the light fixture; and a dimming control signal output by the microcontroller to an input of the driver configured for controlling the driver of the light fixture to adjust the intensity of the light fixture by adjusting a current provided to the first LED group and the second LED group based on the intensity setting for the light fixture, wherein the current is proportional to a voltage value of the dimming control signal.

2. The light fixture controller of claim 1, wherein the dimming control signal comprises a 0-10V control signal having a value varying between 0 and 10V.

3. The light fixture controller of claim 1, wherein the first control signal or the second control signal comprises a pulse width modulation (PWM) signal.

4. The light fixture controller of claim 1, wherein the driver of the light fixture is a single-channel driver.

5. The light fixture controller of claim 1, wherein the one or more interfaces comprise at least one of, switches, tactile buttons, break-away PCB tabs or traces, near field communication (NFC)-TAG interfaces, digital wired network communication interfaces, wireless communication interfaces, or optical communication interfaces.

6. A method for controlling color temperature, light distribution, and intensity of a light fixture, comprising:

receiving, at a light fixture controller of the light fixture, a color temperature setting, an intensity setting, and a light distribution setting for the light fixture, the light fixture comprising a plurality of LED groups comprised of one or more portions of a plurality of LEDs wherein each portion of the LED group is located at a corresponding area of the light fixture, a driver for powering the plurality of LED groups, each of the plurality of LED groups comprising LEDs configured to produce light at a particular color temperature, and switches operably connected to the portions of the plurality of LEDs comprising the LED groups; determining, by the light fixture controller, an open/closed state of the switches operably connected to the portions of the plurality of LEDs to enable one or more portions of the LED groups to receive power from the driver,

13

wherein the open/closed state of the switches is based on the light distribution setting; determining, by the light fixture controller, an ON/OFF cycle for the plurality of LED groups based on the color temperature setting, wherein the ON/OFF cycle comprises multiple time periods, and during each of the multiple time periods, at least one of the enabled portions of one of the plurality of LED groups is turned ON and the enabled portions of remaining LED groups of the plurality of LED groups are kept OFF, and wherein a ratio between the multiple time periods is determined based on the color temperature setting for the light fixture; generating, by the light fixture controller, a plurality of control signals to control the switches based on the determined open/closed state of the switches and the determined ON/OFF cycle; generating, by the light fixture controller, a dimming control signal configured for controlling the driver of the light fixture to adjust the intensity of the light fixture by adjusting a current provided to the plurality of LED groups based on the intensity setting for the light fixture, wherein the current is proportional to a voltage value of the dimming control signal.

7. The method of claim 6, wherein the dimming control signal comprises a 0-10V control signal having a value varying between 0 and 10V.

8. The method of claim 6, wherein each of the plurality of control signals comprises a pulse width modulation (PWM) signal.

9. The method of claim 6, wherein the driver of the light fixture is a single-channel driver.

10. The method of claim 6, wherein the color temperature setting or the intensity setting for the light fixture are received through at least one of a switch, a tactile button, a break-away PCB tab or trace, a near field communication (NFC)-TAG interface, a digital wired network communication interface, a wireless communication interface, or an optical communication interface.

11. A light fixture, comprising:

a first lighting element group comprising two or more portions of a first plurality of lighting elements wherein a first portion is located at a first area of the light fixture and a second portion is located at a second area of the light fixture and the portions of the first lighting element group are configured to produce light at a first color temperature;

a second lighting element group comprising two or more portions of a second plurality of lighting elements wherein a first portion is located at the first area of the light fixture and a second portion is located at the second area of the light fixture and the portions of the second lighting element group are configured to produce light at a second color temperature;

a plurality of switches operably connected to the portions of the lighting element groups;

a driver; and

a light fixture controller configured for performing operations for controlling color temperature, light distribution, and intensity of the light fixture, the light fixture controller comprising:

one or more interfaces configured for receiving at least a color temperature setting, an intensity setting, and a light distribution setting for the light fixture; and

14

a microcontroller configured for generating control signals based, at least in part, upon the color temperature setting, and the light distribution setting for the light fixture, wherein the control signals comprise a first control signal, a second control signal, a third control signal, and a fourth control signal, wherein:

the first control signal controls a first switch connected to the first portion of the first lighting element group to select the first portion of the first lighting element group to receive current provided by the driver based on the light distribution setting and based on an ON/OFF cycle, the second control signal controls a second switch connected to the first portion of the second lighting element group to select the first portion of the second lighting element group to receive current provided by the driver based on the light distribution setting and based on the ON/OFF cycle, the third control signal controls a third switch connected to the second portion of the first lighting element group so the second portion of the first lighting element group remains off, and the fourth control signal controls a fourth switch connected to the second portion of the second lighting element group so that the second portion of the second lighting element group remains off;

the first control signal turns on the first switch only for a first duration of the ON/OFF cycle and the second control signal turns on the second switch only for a second duration of the ON/OFF cycle, wherein the ON/OFF cycle comprises multiple time periods, and during each of the multiple time periods, one of the first lighting element group or the second element group of the light fixture is set to be on and the other is set to be off; and

a ratio between the first duration and the second duration is determined based, at least in part, upon the color temperature setting for the light fixture.

12. The light fixture of claim 11, wherein the control signals further comprise a dimming control signal configured for controlling the driver of the light fixture to adjust a current flowing through both the first lighting element group and the second lighting element group based on the intensity setting for the light fixture.

13. The light fixture of claim 12, wherein the driver is a single-channel driver.

14. The light fixture of claim 13, wherein the dimming control signal comprises a 0-10V control signal having a value varying between 0 and 10V.

15. The light fixture of claim 11, wherein the first control signal or the second control signal comprises a pulse width modulation (PWM) signal.

16. The light fixture of claim 11, wherein a lighting element is a light-emitting diode (LED) or an organic light-emitting diode (OLED).

17. The light fixture of claim 11, wherein the one or more interfaces comprise at least one of, switches, tactile buttons, break-away PCB tabs or traces, near field communication (NFC)-TAG interfaces, digital wired network communication interfaces, wireless communication interfaces, or optical communication interfaces.
